CLOSURE FOR A FOOD MOLD OR THE LIKE

James B. Swett, Barrington, and Robert F. Bateman, Providence, R.I., assignors to Rexall Drug and Chemical Company, Los Angeles, Calif., a corporation of Delaware

Filed Aug. 14, 1967, Ser. No. 8,263

Term of patent 14 years

(Cl. D44—1)

FIG. 1

FIG. 2

FIG. 3

FIG. 4

FIG. 1 is a perspective view of a closure for a food mold or the like showing our new design;

FIG. 2 is a side elevational view;

FIG. 3 is a top plan view;

FIG. 4 is a bottom plan view.

The essential features of our invention are shown in solid lines.

We claim:

The ornamental design for a closure for a food mold or the like, substantially as shown and described.
